UNITED STATES PATENT OFFICE.

FREDERICK D. DAVIS, OF LUDINGTON, MICHIGAN.

PLASTIC MOLD.

SPECIFICATION forming part of Letters Patent No. 770,846, dated September 27, 1904.

Application filed July 3, 1903. Serial No. 164,153. (No model.)

To all whom it may concern:

Be it known that I, FREDERICK D. DAVIS, a citizen of the United States, residing at Ludington, in the county of Mason and State of Michigan, have invented certain new and useful Improvements in Plastic Molds; and I do hereby declare the following to be a full, clear, and exact description of the invention, such as will enable others skilled in the art to which it appertains to make and use the same.

My invention relates to plastic molds or forms for hollow cement, concrete, or similar blocks. Its object is to provide a readily adjustable and removable form especially adapted for the formation of hollow or fire-proof concrete or cement blocks. To this end it comprises the combination of parts as set forth in the appended claims, especially a pair of longitudinally and laterally adjustable side plates and a pair of pivoted central plates, forming an air-space.

In the accompanying drawings, Figure 1 is a perspective view of my device ready for use, but without the end plates. Fig. 2 is a plan view with the end plates in place. Fig. 3 is a section on the line *a a* of Fig. 2. Fig. 4 is a side elevation of the end plate; and Figs. 5, 6, and 7 are details.

In the drawings, 1 represents a series of hollow blocks or bricks, the dotted lines indicating a further building up upon different lines.

2 3 represent side plates, and 4 5 center plates, of the form.

6 represents a bent L-shaped bar. There are two of these bars, and they are joined by angle-bars 7, secured to them, and having slots 8, through which pass the shafts of binding-nuts 9, taking into the side of the plates 2 and 3, thus permitting the plates to be adjustably secured, in effect, to the bars 6. L-shaped bars 10 are secured to the plate 3 and project over the plates 2, 3, 4, and 5, parallel with the arms of the bars 6 and pivoted thereto at 11, a number of perforations being shown to indicate scope of adjustment.

12 represents an upright to which the central plate is secured. I have shown four in

use, two at each end, their upper ends lying between a bent-out part of the bar 6 and the bar 10.

13 represents a nut securing the upright 12. I have shown a number of perforations to indicate adjustability.

14 is a connecting-rod running along the bottom of the air-space between the central plates, carried by a bracket 15 on one of the plates and carrying at each end an eccentric-disk 16. Each of these disks is slotted at opposite sides and each slot takes over a pin on one of the central plates. A link 17 is connected to each eccentric and at the top takes over one of several pins 18.

19 is a lever-arm pivoted to one of the central plates and connected by a link 20 to the connecting-rod 14, so that when it is drawn over in either direction it will rotate the rod 14 and draw together or push apart the central plates at the bottom, swinging them on the pivoted uprights 12.

21 is an end plate, with a lug 22 at the bottom at each side taking over a pin 23 on the side plate and a lug 24 at the top taking under a pin 25.

26 is a hand-lever pivoted at 27 to the end plate on each side and having a hooked inner arm 28, which takes over the pin 25.

29 is an adjusting-rod, one at each side, having a threaded part which passes through a collar 30 on the end plate. At the bottom each rod takes into an angle-iron 31, slotted to receive a pin 32 on the end plate. It is apparent that by turning the rods 29 the device may be used to adjust or level the form.

33 is a plate which may be used to cover the end of the air-space when a corner-stone is being molded, an arrangement for that purpose being shown.

With the parts assembled as they are in Fig. 2 an end block may be cast such as is indicated by dotted lines in Fig. 1. With the parts arranged as in Fig. 1 a block may be cast fitting up against a previously-molded block and having a central space by simply pouring the material on each side of the central plates. When the mixture is in place

and fixed, the central plates may be loosened by moving over the lever 19 so as to draw together the bottoms of the plates.

When it is desired to mold a form such as 5 shown at Fig. 2, the nuts 9 may be loosened as the side plates 4 5 move forward, and again secured, the scope of adjustability being obvious. To enlarge the block, all that is required is to loosen the pivot 11 and change it 10 to another set of perforations.

Having fully described my invention, what I claim is—

1. In a plastic mold, the combination of substantially parallel outer plates, and substantially parallel inner plates adjustably coupled. 15
2. In a plastic mold, a pair of laterally and longitudinally adjustable side plates, and a pair of pivoted central plates forming an air-space. 20
3. In a plastic mold, the combination of a pair of central plates, a pair of longitudinally-adjustable side plates, and a separable end plate. 25

4. In a plastic mold, the combination of a pair of adjustable central plates, a pair of longitudinally-adjustable side plates, an end plate for the central plates, and an end plate embracing the end of the side plates. 30

5. In a mold for plastics, the combination of a series of side and central plates, an end plate, pins on the plate, slotted angle-iron feet playing over the pins, and threaded adjusting-rods passing through the angle-irons. 35

6. In a plastic mold, the combination of side plates connected by adjustable bars, a pair of central plates, a connecting-rod, an eccentric at each end of the rod engaging each central plate, an arm leading from the eccentric to the top of the plate, means for securing the arm, and an operating-lever. 40

In testimony whereof I affix my signature in presence of two witnesses.

FREDERICK D. DAVIS.
